UNITED STATES PATENT OFFICE

152,523

DESIGN FOR A BOX OR THE LIKE

John L. Duncan and Bryce Martin, Chicago, Ill.

Application December 26, 1946, Serial No. 135,762

Term of patent 14 years

(Cl. D58—11)

To all whom it may concern:

Be it known that we, John L. Duncan and Bryce Martin, citizens of the United States, residing in Chicago, in the county of Cook and State of Illinois, have invented a new, original, and ornamental Design for a Box or the like, of which the following is a specification, reference being had to the accompanying drawing, forming a part thereof.

We claim:

The ornamental design for a box or the like, as shown.

JOHN L. DUNCAN.
BRYCE MARTIN.
